CARRIAGE DRIVING AND HAMMER
RETURNING MEANS

Alfred E. Oswald, Hackensack, N. J., assignor, by
mesne assignments, to Ralph C. Coxhead Cor-
poration, New York, N. Y., a corporation of
Delaware

Application July 7, 1931, Serial No. 549,170

8 Claims. (Cl. 197—49)

This invention relates to typewriting machines and more particularly to improved power means for driving the carriage and for restoring the printing hammer against the action of its actuating spring. The invention is shown as applied to a varityper writing machine and is in the nature of improvements which may be used with parts shown in the application of Frank Spaloss, Serial No. 549,210 filed July 7, 1931.

In said application there is provided a power means, the strength of which is always the same at each operation thereof. It comprises a spring connected by suitable means with the carriage and the printing hammer to assist in driving the carriage and to return the hammer after each printing operation. Said spring is energized at each letter space movement of the carriage, by means including an electro-magnet or solenoid connected in circuit with a normally open switch, the latter being operable by any one of the key levers to close it and thus energize the solenoid to cause its actuation. The solenoid operates a reciprocating device including a lever, to which is connected the driving spring, and upon which is pivotally supported a pawl to co-operate with a ratchet wheel, associated with the escapement wheel, to assist in driving the latter, said escapement wheel being connected in the usual manner through a dog carrying lever with the printing hammer.

A feature of the present invention is to automatically break the solenoid circuit after each operation thereof so as to prevent heating which may otherwise result from carelessly holding the key lever depressed.

Another feature of the invention relates to the construction of the solenoid so that it may be used for alternating current or direct current and for different voltages as, for example, 110 volts or 220 volts.

Other features and advantages will hereinafter appear.

In the drawings which form part of the specification,

Fig. 1 is a sectional side view of the machine taken on the line 1—1 of Fig. 4;

Fig. 2 is a detail sectional view taken on the line 2—2 of Fig. 4 showing the switch and its actuating means;

Fig. 2A is a detail view of the blocks forming part of the switch;

Fig. 3 is a sectional top plan view of the machine, some of the parts being broken away and others being omitted;

Fig. 4 is a rear view of the machine, parts being broken away;

Fig. 5 is a diagram of the electric circuit;

Fig. 6 is a fragmentary rear view showing the solenoid operating to cock or set the power means and showing the switch about to be opened;

Fig. 7 is a horizontal section through the solenoid;

Fig. 8 is a vertical section through the solenoid taken on the line 8—8 of Fig. 7;

Fig. 9 is a detail view of a modified form of plunger for the solenoid; and

Fig. 10 is an end view of the modified form of plunger.

Similar characters refer to similar parts throughout the several views.

The invention is shown applied to a varityper writing machine which includes a main frame 20 to which is secured a track 21 upon which a carriage 22 is mounted to travel back and forth transversely of the machine. The carriage is provided with a bar 23 which co-operates with the track 21 through anti-friction rollers or balls 24 to guide said carriage. The carriage is further guided by a bar 25 at its upper end co-operating with a roller 26 mounted on the main frame 20.

The carriage is urged in a letter feed direction by a carriage propelling means or spring drum 30 (Figs. 3 and 4) rotatably supported by a shaft 31 (Fig. 4) on the main frame 20; the spring drum being connected to the carriage by a strap or draw band 32. Letter feed movements of the carriage are effected by escapement mechanism, indicated generally by the numeral 33, which is actuated at each operation of the key levers 34.

The escapement mechanism includes a pinion 35 to be engaged by a rack 35a on the carriage, said pinion being connected to a shaft 36 supported in a rear cross-bar 37 of the main frame and a lug 38 of said frame. An escapement wheel 48 is rotatively supported on the escapement shaft 36 and has secured thereto a ratchet wheel 49. The ratchet wheel 49 is engaged by a pawl 51 pivoted by a screw 52 on an arm 53 secured to a hub 54, the latter being fastened to the shaft 36. Thus by this connection the escapement wheel is connected to be rotated by the carriage through the medium of the shaft 36 in a letter space direction. Said escapement wheel is normally held against rotation by a loose dog 56 pivoted by a stud 57 on a lever 58 pivoted on the escapement shaft 36, the downward movement of the lever 58 being limited by a stop 59 of a fixed bracket 60 secured to the

rear bar 37 of the machine frame. While the carriage is being returned the pawl 51 rides freely over the teeth of the ratchet 49 against the action of a spring 61 connected between an ear 62 of the pawl 51 and a pin 63 on the arm 53. A spring pressed pawl 64 (Fig. 4) prevents backward rotation of the escapement wheel.

To actuate the escapement mechanism 33 and thus feed the carriage at each printing operation, 10 the key-levers 34 when actuated about fulcrums 65, engage a universal bar 66 of a frame 67 to swing the latter about a fulcrum 68. An arm 69 of the frame 67, when the latter is actuated, swings downwardly to actuate a dog rocker 70 15 through the medium of a set screw 71 engaging a tail 75 of the dog rocker to carry a fixed dog 73 into engagement with the teeth of the escapement wheel 48.

The dog rocker 70 is provided with an arm 74 20 having a slot 75 into which extends a pin 76 from the loose dog 56, whereby the loose dog is swung out of engagement with the escapement wheel; the dog carrying lever 58 being connected to a printing hammer 77 by means of a stud 78 to be 25 actuated thereby during a printing operation of said hammer which is actuated in a manner hereinafter described. As the pin 76 travels upwardly in the slot 75 the dog 56 is guided into the path of the next succeeding tooth of the escapement 30 wheel. Subsequently the dog rocker 70 is brought back to normal upon the return of the arm 69 to disengage the dog 73 from the escapement wheel, whereupon the escapement parts and the printing hammer 28 are restored to normal.

35 The printing instrumentalities include a type carrier or shuttle 80 having types 81 with which a head 82 of the hammer 77 co-operates to print against an interposed work sheet 83, the work sheet being fed up and down by suitable feed 40 rollers 84 and 85 supported on the carriage 22. The type shuttle 40 is curved to conform with a cylindrical anvil 86 by which it is carried through the medium of a thin flange 87 extending through a slot 88 in said anvil.

45 To actuate the type shuttle 80 the flange 87 has connected thereto a lever 89 secured to a sleeve 90 to rotate about the axis of a shaft 91; the sleeve 90 being supported on a bar 92, of the main frame, on which it is maintained by a screw 93 engaging 50 a flange 94 at the lower end of the said sleeve.

The shuttle actuating lever 89 may be actuated, from a central position, in opposite directions by either of two arms 95, about the shaft 91, said arms being actuated, one at a time, in a manner hereinafter described, to carry the selected type of the shuttle 80 to the printing point, the types being accurately positioned by means of indexing pins 96 operable by the key levers 34 to project their upper ends into the path of the 60 shuttle lever 89 to arrest the latter. Subsequently the hammer is actuated, under the control of the escapement mechanism, by a spring 96, said hammer being secured to a shaft 97, Fig. 3, supported by pivot screws 98 on the main frame 20.

65 Each of the arms 95 which operates the shuttle actuating lever 54 forms part of a frame 97, each frame being supported to swing about a pivot 98 on a fixed bracket 99. Each frame 97 also includes a bar 100 extending towards the middle 70 of the machine and over the key lever 34 to one side of the middle of the machine, so that if any one of the key levers is operated the associated one of the frames 97 is actuated thereby against the action of a return spring 101. The upper end 75 of the arm 95 is thus swung rearwardly to actuate

the lever 89 and shuttle 80 to select the type as above described. The arms 95 may engage the lever 89 directly, if desired, or they may engage a resiliently supported slide 102 thereon like that shown in the application of Frank H. Trego, Serial No. 412,651, filed December 19, 1929, which slide permits a slight movement of frame 97, after the arm 89 has been arrested, to actuate the escapement mechanism.

When the escapement is operated the release 10 of the printing hammer is effected from the escapement wheel by the actuation of the dog rocker 70 as previously described. It is then actuated, by the spring 96 connected thereto, to print.

The release of the carriage may be effected as 15 in the above mentioned Spaloss application by means which includes a release arm 105 connected to a thrust rod or plunger 106 (Figs. 1 and 4) which is slidably supported on the hub 54 at the 20 end of the escapement shaft 36. The inner end of said plunger is provided with an annular cam 107 which, when the plunger is moved inwardly, engages the ear 62 of the pawl 51 to swing the pawl 51 about the pivot 52, in any position which it may occupy about the axis of the escapement 25 shaft, to disengage said pawl from the ratchet. Thus the carriage may be released from the escapement.

The means which assists in returning the printing hammer includes a spring 125 (Fig. 4) one 30 end of which is connected to a bracket 127 secured to the rear bar 37 of the machine frame by screws 128. The other end of the spring is connected to a lever 129 pivoted by a stud 130 on said bracket 127, the spring tending to rock the lever 35 129 in a clockwise direction to rotate the ratchet 49 and the escapement wheel 48 secured thereto in the same direction through the medium of a pawl 131 supported on the shoulder of a headed stud or screw 132, the pawl 131 being held in contact with the ratchet 49 by a spring 133.

It will be understood that whenever the lever 129 is actuated in a counterclockwise direction, (Fig. 4) the pawl 131 is cocked as in Fig. 6 against the action of the actuating spring 125, said pawl 45 snapping over one of the teeth of the ratchet 49. Thus the spring 125 is energized at each actuation of the lever 129 in this direction which occurs at each letter space movement of the carriage and after the printing operation, and is caused by 50 means hereinafter described, under the control of the key levers 34. After the reciprocatory means including the lever 129, pawl 131 and spring 125, has been cocked, it is released and rotates the escapement wheel to restore the printing 55 hammer 77, against the action of its spring 96, through the medium of the dog 56 and the dog supporting lever 58.

To actuate the lever 129 and thus increase the strength of the spring 125 there is provided an 60 electromagnet or solenoid 135 held on the rear bar 37 of the machine frame by a strap 136 secured to said rear bar by screws 137, and a bracket 138 secured to an end piece 139 of the solenoid by screws 140, said bracket 138 being secured to the 65 machine frame by screws 141. The solenoid when it is energized, as hereinafter described, sucks in a plunger 142 to draw on a link 143 pivotally connected thereto by a pin 144. The other end of the link 143 is connected to the lower end of the 70 lever 129, by a shouldered screw 145, to actuate the lever 129 in a counterclockwise direction when the solenoid is energized.

To limit the movement of the plunger 142, and its connected parts, when actuated by solenoid 75

135, the lever 129 has a lip 146 to engage a stop 147 secured to the bar 37 of the main frame.

The operation of the solenoid is effected by a normally open switch 150 (Fig. 4) which may be closed at the proper time by any one of the key levers 34 to cause an electric current to flow from a source of supply 151 (Fig. 5) through conductor 152, main switch 153, conductor 154, resistance 155, conductor 156, solenoid 135, conductor 158, switch 150, conductor 159 to ground 160. When the actuation of the solenoid is thus effected the escapement operating mechanism including the pawl 131 is cocked thereby as above described.

15 The switch 150 includes a contact spring 163 to which is connected the conductor 159 and a contact spring 164 to which is secured the conductor 158. Said contact springs are supported in slots 165 and 166 formed in the oppositely disposed faces of blocks 167 and 168 of insulating material, said blocks being secured to the rear bar 37 of the main frame by a screw 169.

20 To close the switch 150 there is provided on the arm 69 of the universal bar frame a bracket 170 having secured thereto a finger 171 which, whenever the universal frame 67 is operated by the key levers 34, as above described, flexes the contact spring 164 downwardly against the contact spring 168 and thus close the switch 155, whereupon the solenoid 135 operates to cock the pawl 131 against the action of the spring 125 as previously described.

25 Provision is made to automatically cut off the current to the solenoid 135 upon the completion of its operation so as to prevent heating of the solenoid which would otherwise result when the active key lever is carelessly held depressed. To this end there is adjustably secured to the link 143, which is operated, by the solenoid plunger 142, a projection 175 by a screw 176, said projection to engage the finger 171 which is resilient, as in Fig. 6 to move the free end thereof from the contact spring 164 to allow the latter to return to normal, thus opening the switch 155 to de-energize the solenoid 135. It will be understood, see Fig. 6, that the pawl 131 has already reached its cocked position before the switch is opened, so that the spring 125 is ready to function, through the medium of said pawl and the ratchet 49 to return the printing hammer as previously described. Upon the return of the universal bar 66 to normal, the finger 171 snaps back into place over the end of the contact spring 164.

30 To prevent the current from flowing into the finger 171, there is secured to the upper face of the contact spring 164 a block 177 of insulating material which projects slightly beyond the end of said contact spring to prevent touching the finger 164 when the latter is pushed off the contact spring.

35 The operation of the switch is semi-automatic since the closing thereof is performed manually by means under the control of the key levers, and the opening thereof is effected automatically by the solenoid, the operation of which is brought about by said switch.

40 To prevent arcing and freezing of the contacts of the switch 150 there is connected in parallel with the switch a condenser 180 by conductors 181 and 182. Said condenser acts to momentarily absorb the energy that would otherwise occur across the contact points while the switch is opening.

45 The solenoid is of the iron-clad plunger type. It comprises a sleeve or bushing 185 (Fig. 7) upon

5 which is wound a coil 186 composed of enameled, single silk insulated soft copper wire, the coil extending from one end to the other of the sleeve, only a few of the windings of the coil being shown at each end thereof. Two discs 187 of insulating material, such as fibre, form with the sleeve a spool to carry the coil 186. The spool is contained within a cylindrical shell 188 of steel which shell is closed at its ends by metal discs 139 and 189 also of steel, said discs being secured 10 to the shell 188 by pins 190. A core 191 is contained within the sleeve to form with the plunger 142 discs 139 and 189, and shell 188, a path for the magnetic flux. The bushing 185 is composed of brass or any other non-magnetic material to 15 avoid friction of the plunger 142 which would otherwise be produced.

20 The core 191 is adjustable axially of the bushing by a screw 192, secured to said core, and is threaded into the bracket 138 so that upon the 25 rotation of said screw the core may be adjusted to its proper position. The core is held in its adjusted position by a lock nut 193 on the screw 192 and bearing against the face of the bracket 138.

25 The plunger 142 is provided at its end with an escutcheon pin 194, of brass, to prevent any possibility of sticking to the core 191, due to residual magnetism, which may otherwise result if the end of the core and plunger touch each other.

30 Provision is made to prevent eddy or secondary currents which would otherwise be generated in the solenoid when it is used on alternating current. Said current if allowed to exist would greatly heat and thus lower the efficiency of the 35 solenoid. The eddy current opposes the primary current through the solenoid winding and thus reduces the magnetic pull on the plunger 191. Such eddy or secondary current would put an 40 extra load on the coil 186 and would result in more current consumption.

35 To prevent said eddy currents all of the metal parts, bushing 185, discs 139 and 189, and shell 188, plunger 142 and core 191, are provided with slots 196, 197, 198, 199, and 200, respectively. 45 It will be understood that the slot 196 is near the upper sides of the bushing to prevent oil from dropping into the coil if someone should attempt to oil or lubricate the plunger of the solenoid.

40 The plunger 142 and the core 191 are solid and 50 are provided with slots 199 and 200 respectively. To produce a similar effect, that of preventing eddy currents, they may each be constructed as the plunger 201, illustrated in Figs. 9 and 10, which is composed of laminations 202 held together by rivets 203.

45 A shading coil 205 comprising a semi-circular tube of copper is secured to the end of the core 191, and causes the solenoid to operate on split phase, and is effective when the solenoid is used 60 on alternating current. With the shading coil there is produced an effect similar to a two phase circuit as if the solenoid has a duplicated winding. When one frequency of a single phase circuit produces magnetism in the solenoid the shading 65 coil chokes back some of this magnetism and thereby produces magnetism of its own when the original phase cycle is reversed through zero. In other words the magnetism produced by the shading coil is 180 degrees out of phase. This 70 produces a more uniform magnetic pull and decreases the magnetic hum which is due to the alternating current. It will be understood that the shading coil functions only on A. C. current and does not interfere when D. C. current is used. 75

The resistance 155 is detachably connected in the circuit so that it may be substituted by any one of a plurality of similar resistances, each resistance having a different ohmic value to compensate for different voltages and D. C. and A. C. current. Each resistance comprises a suitably insulated winding 210 (Figs. 1, 3 and 4) the ends of which are provided with metal tips or ferrules 211 to be received in resilient clips 212 and 213 extending from brackets 214 and 215 secured to a block 216 of insulating material suitably fastened to the machine frame; the brackets 214 and 215 having secured thereto the conductors 154 and 156.

15 An object of using a resistance 155 in series with the solenoid is primarily to allow the line voltage to overcome the inductance of the solenoid more quickly and to keep the current at a safe fixed value. The inductance exists all the time while the A. C. current is flowing; consequently a lower resistance is used than with D. C. current. On D. C. current just as soon as it is turned on the rise in magnetism chokes back the solenoid current, causing the current to rise from 20 zero to a maximum in a longer interval of time than it would require if resistances of the same ohmic value were used in place of the solenoid winding. Thus it will be understood that the voltage drop across the series resistance and the 25 inductance of the solenoid winding will automatically adjust itself advantageously, whereas the voltage drop across the solenoid winding will at first (on start of current) be at its maximum and gradually fall, that is the voltage will drop 30 across the solenoid until the current reaches a maximum. The advantage of this arrangement is that the same solenoid may be used for the various conditions of voltage and kind of current.

Although some of the devices above described 40 may not in themselves be novel, it should be understood that there is a decided advantage of using in combination the solenoid with a shading coil therein, and connecting the solenoid in series with a resistance to give an automatic voltage 45 control over the inductive winding of the solenoid, use of a condenser in the circuit to prevent sparking and freezing of the switch contacts, and the use of a semi-automatic switch whereby the current is cut off to prevent heating of the solenoid 50 when an operator carelessly holds down an actuated key lever.

While certain preferred embodiments of the invention have been shown and described, it 55 should be understood that changes in the form, arrangement, proportions, sizes and details thereof may be made without departing from the scope of the invention as defined in the appended claims.

I claim:

- 60 1. In a typewriting machine, the combination of key levers, a selectively settable type carrier, means operable by said key levers to effect the setting of said type carrier, a hammer to co-operate with said type carrier, means operable by said key levers to effect the actuation of said hammer, spring actuated means to return said hammer, electric means, means operable by said key levers to render the electric means effective to cock said spring actuated means at each operation of any one of the key levers, and means whereby the electric means may be rendered ineffective after the spring has been cocked and while the key lever is still in its operated position.
- 65 2. In a typewriting machine, the combination of key levers, a selectively settable type carrier,

means operable by said key levers to effect the setting of said type carrier, a hammer to co-operate with said type carrier, means operable by said key levers to effect the actuation of said hammer, operating means, an electro-magnet the actuation of which is effected by the key levers to cock said operating means at each actuation of any one of said key levers, means to automatically render said electro-magnet ineffective independently of the key levers after the operating means has been cocked so as to avoid heating of the electro-magnet if the return of the key lever is delayed, and means actuatable by the operating means to cock said hammer.

3. In a typewriting machine, the combination of key levers, a printing hammer, means operable by said key levers to effect the actuation of the hammer, spring actuated means to return said printing hammer, electrically operated means including an element to cock the spring actuated means, means operable by the key levers to render the electrically operated means effective at each depression of any one of the key levers, and means associated with said element to render the electrically operated means inactive independently of the active one of the key levers after the spring actuated means has been cocked thereby so as to prevent heating of the electrically operated means if the return of a key lever is delayed.

4. In a typewriting machine, the combination of key levers, a printing hammer, means operable by said key levers to effect the actuation of said hammer, means to return said hammer after each printing operation, an electro-magnet to energize said hammer returning means, means actuatable by the key levers to render effective the electro-magnet at each actuation of a key lever, and means independent of the key levers to render said electro-magnet ineffective after each printing operation of the hammer to prevent heating of the electro-magnet if the return of the key lever is delayed.

5. In a typewriting machine, the combination of key levers, a printing hammer, means operable by said key levers to effect the actuation of the hammer, means to return said printing hammer after each printing operation, a solenoid having a plunger, means including a bar connected to said plunger whereby the hammer returning means may be energized by the solenoid, a normally open switch electrically connected with said solenoid, means including a resilient element operable by the key levers to close said switch to render the solenoid effective, and an adjustable device on said bar to operate and disengage the resilient element of the switch closing means from the switch to effect the opening of the latter after each printing operation of the hammer.

6. In a typewriting machine, the combination of key levers, a printing hammer, means operable by said key levers to effect the actuation of the hammer, spring actuated means to return said printing hammer, electric means to cock the spring actuated means, an element operable by the key levers to render the electric means active at each depression of any one of the key levers, and means to automatically render said element ineffective after the spring actuated means has been cocked by the electric means so as to render the latter ineffective while the active one of the key levers is still operated to thus prevent heating of the electric means.

7. In a typewriting machine, the combination

of key levers, a selectively settable type carrier, means operable by said key levers to effect the setting of said type carrier, a hammer to cooperate with said type carrier, means operable by 5 said key levers to effect the actuation of said hammer, a spring, means operable by said spring to return said hammer, means including an electro-magnet to energize said spring, means including a switch operable by and upon each actuation of any one of the key levers to render effective said electro-magnet, and means to automatically render the electro-magnet ineffective after it has energized said spring and while the key lever is still in its actuated position.

10 8. In a typewriting machine, the combination of printing instrumentalities including two ele-

ments, namely a settable type carrier and an element to cooperate with any one of the types to cause them to print, means operable by said key levers to effect the setting of said type carrier, means to effect the actuation of one of said printing elements toward the other to effect the printing, means including a spring to return the operated printing element, electric means, means operable by said key levers to render the electric means effective to cock the means which includes 10 the spring, at each actuation of any one of the key levers, and means whereby the electric means may be rendered ineffective after the means including the spring has been cocked and while the active key lever is still in its actuated position. 15

ALFRED E. OSWALD.
